CLAIM

An ornamental design for a massage gun extension arm, as shown and described.

DESCRIPTION

FIG. 1 is a front perspective view of a massage gun extension arm showing my new design;

FIG. 2 is a perspective view thereof;

FIG. 3 is a side view thereof;

FIG. 4 is an end view thereof; and,

FIG. 5 is an opposite end view thereof.

The broken lines shown in the drawings are for the purpose of illustrating environmental structure, which form no part of the claimed design.
